UNITED STATES PATENT OFFICE.

KENNEDY DOUGAN, OF MINNEAPOLIS, MINNESOTA.

TEMPERATURE-REGULATING MEANS.

Application filed May 8, 1919. Serial No. 295,766.

To all whom it may concern:

Be it known that I, KENNEDY DOUGAN, a citizen of the United States, residing at Minneapolis, in the county of Hennepin and State of Minnesota, have invented certain new and useful Improvements in Temperature-Regulating Means, of which the following is a specification.

My invention relates to means for regulating the heating effect of steam radiators or other containers in which heating fluid is confined, the heat being radiated through the walls of the container, and the object of my invention is,—

15 To provide means for increasing or decreasing the amount of heating surface to the amount necessary to give the required heat: I attain this object by the mechanism illustrated in the accompanying drawing, in which,

20 Fig. 1 is a vertical central section through a steam container with my heat regulating means shown attached thereto, also shown in vertical section with some of the parts shown in full lines.

25 Fig. 2 is a similar section, enlarged, with portions broken away.

30 Fig. 3 is a central vertical section partly in full lines, of parts shown in Fig. 2.

35 Fig. 4 is a horizontal section taken on the line A, Fig. 2.

40 Fig. 5 shows a slightly modified form of the device applied to an ordinary steam radiator such as is commonly used for house warming purposes, the radiator being shown in elevation and the heat regulating device partly in vertical section, and partly in full lines.

Similar numerals refer to similar parts throughout the several views.

The drawing is largely diagrammatic. 1 is a cylindrically shaped steam container in which steam is carried at boiler pressure; 2, the pipe which carries the steam from the boiler to said steam container; 3 and 4, pipes which connect the upper and lower ends of said steam container with the upper and lower ends respectively of a comparatively small cylinder 5, and it is in this cylinder that the temperature controlling means is located and consists of a plurality of pipes of different heights having their upper ends open and their lower ends adapted to be selectively opened and maintained open one at a time. The heating effect is regulated by the amount of heating surface in use

and this by the portion of the steam container that is allowed to fill with water from the boiler or with condensed steam.

6 is a cylinder formed integral with cylinder 5 but separated therefrom by partition 7; 8, a pipe conducting the water of condensation back to the boiler; 9 is a round rod having its lower end screw-threaded into partition 7 as shown, its upper end extending through a stuffing box at the upper end of cylinder 5 as shown, 11 being a stuffing box screwed into the upper end of cylinder 5; 12, a gland screw threaded into stuffing box 11; 13, the packing; 14, a hand wheel secured to rod 9.

In order that conduit 19 may be caused to register with any one of conduits 20, 21, 22 or 23, hand wheel 14 has four graduation marks on its periphery which marks are equi-distant apart and numbered from 1 to 4 inclusive, only two of these marks, 1 and 2, are shown. Slidably mounted upon cylinder 5 in brackets 26 and 26' is an indicator 27 provided with a finger piece 28 by which to move it up or down to bring its upper end close to wheel 14. When one of the graduation marks 1 to 4 on hand wheel 14 registers with an indicator mark (not shown) on the upper surface of indicator 27, its corresponding conduit is in register with conduit 19. Fitting snugly upon the unthreaded portion of rod 9 and supported by a collar 15 formed integral with or rigidly secured to said rod 9, is an annulus 16 provided on its periphery with a projection 17 adapted to reciprocate in a groove 18 formed in cylinder 5. Projection 17 prevents rotation of annulus 16 but permits it to be moved up or down by the means provided, which consists of the screw-threaded portion of rod 9 rotating in partition 7, which is also screw-threaded, and which rod 9 is adapted to be rotated manually by means of hand wheel 14 which is rigidly secured to rod 9, the purpose of which is to raise or lower annulus 16 and with it the pipes 21, 22 and 23 as well as the annulus itself in which hole 20 is formed. Rod 9 is a snug fit in annulus 16 in order to prevent the passage of water between said annulus and said rod but not sufficiently tight to prevent turning by the means provided. Formed in the lower portion of rod 9 is a central vertical conduit 19, not shown in Fig. 1 but clearly shown in Fig. 3 and in dotted lines in Fig. 2. Conduit 19 turns in a horizontal direc-

110

tion near its upper end and registers selectively with any of the four conduits 20, 21, 22 and 23, shown in Fig. 4, conduit 20 being shown also in Fig. 3. It will be noted that 5 there is but one conduit in rod 9, and that by rotating hand wheel 14, rod 9 can be rotated to bring conduit 19 into register with any one of conduits 20, 21, 22 or 23. It is 10 obvious that when one of said conduits is 10 in register with conduit 19 that there will be an open passageway from the upper to the lower side of partition 7 and that water may flow from above partition 7 down through conduit 19 and out through conduit 8 and back to the boiler.

15 The operation is as follows:

When the entire heating effect of the steam container is required conduit 19 is brought into register with conduit 20 the 20 upper surface of which is level with the upper surface of annulus 16 in which said conduit 20 is formed; water will now drain out of steam container 1 down to a level with the upper surface of annulus 16. If 25 any of the other pipes be brought into register with conduit 19 water, that is to say condensed steam, will accumulate in said steam container until it rises above the upper end of said pipe when it will flow out 30 through conduit 19 and prevent the further rise of water in said steam container and in this way maintain a uniform amount of heating surface.

Any portion of the heating surface may 35 be utilized, as by rotating hand wheel 14 the pipes 21, 22 and 23 as well as conduit 20 may be raised or lowered, to cause the water to overflow at any desired height, within the elevation due to one rotation of 40 hand wheel 14, by which is meant that since conduit 19 must always be stopped when in

register with the proper pipe or conduit it will not be possible to adjust the height of the pipes closer than the vertical distance one turn of hand wheel 14 raises annulus 16. 45

In the modified form of the device shown in Fig. 5, 24 is the radiator; 25, the steam supply pipe. The lower portion of rod 9 is not threaded but is adapted to rotate in annulus 16 and is raised or lowered by 50 means of hand wheel 14 which is rigidly secured to the upper end of said rod 9. 29 is a support rigidly secured to cylinder 5 and provides means for carrying the threaded upper end of rod 9.

55 I claim:

In a device of the kind described, a steam container, a hollow vertical cylinder closed at both ends, a partition across said cylinder between its ends, a steam connection between the lower end of said steam container and said vertical cylinder above said partition, and a steam connection between the upper end of said steam container and the upper end of said vertical cylinder, a rod extending through a portion of said vertical cylinder and through said partition, a conduit formed in said rod, leading from its exterior to its interior and from above to below said partition, and discharging into said vertical cylinder, an annulus carried by said rod above said partition, a plurality of vertical conduits of variable heights carried by said annulus, means for bringing the aforesaid conduit in said rod into register with any of the aforementioned vertical conduits of variable heights carried by said annulus, and means for reciprocating said annulus in said cylinder.

75 In testimony whereof I affix my signature.

KENNEDY DOUGAN.
